UNITED STATES PATENT OFFICE.

FRANK CHATEAUNEUF, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

SHOE-SEWING MACHINE.

1,377,312.

Specification of Letters Patent. Patented May 10, 1921.

Original application filed May 7, 1917, Serial No. 166,943. Divided and this application filed October 4, 1918. Serial No. 256,881.

To all whom it may concern:

Be it known that I, FRANK CHATEAUNEUF, a citizen of the United States, residing at Swampscott, in the county of Essex and State of Massachusetts, have invented certain new and useful Improvements in Shoe-Sewing Machines; and I do hereby declare the following to be a full, clear, and exact description of the invention, such as will 5 enable others skilled in the art to which it appertains to make and use the same.

This invention relates to shoe sewing machines of the class or type employed in sewing inseams of shoes.

15 The primary object of the invention is to improve the construction and operation of certain parts of inseam shoe sewing machines with a view of enabling the shoe to be turned more readily, and of avoiding the weakening of the between substance by making unnecessary punctures therein or by tearing or cutting the same.

With this object in view certain features 25 of the invention relate to a novel and improved arrangement and mode of operation of the feed point for machines of this type. In the illustrated form of the invention the feed point is mounted on the channel guide but certain features of the invention are not 30 limited to a feed point mounted in this manner. In this illustrated construction the channel guide is made up of two parts, the work-engaging ends of which are arranged side by side, and the parts of the guide are 35 relatively actuated during each cycle of operations to project the feed point carried by one of the parts of the guide beyond the acting end of the other part, and to withdraw it back of the acting end of the latter. 40 The advantages secured by the various novel and improved features will be fully explained in the following description.

The features of the invention will be readily understood from the accompanying 45 drawings illustrating a machine embodying the invention in its preferred form and the following detailed description of the construction therein shown.

In the drawings Figure 1 is a view in side 50 elevation of a machine embodying the invention looking from the right; Fig. 2 is a view in front elevation of a portion of the machine illustrating particularly the feed mechanism; Fig. 3 is a plan view of the

mechanism shown in Fig. 2; Fig. 4 is a detail view in side elevation partly in section, illustrating particularly the feed point and channel guide mechanism; Figs. 5, 6, 7 and 8 are diagrammatic views illustrating the mode of operation of the feed point and 60 channel guide; Fig. 9 is a detail view illustrating particularly the manner in which the feed point penetrates the stock.

The machine illustrated in the drawings 65 is an inseam shoe sewing machine having the same general construction and mode of operation as the machine illustrated and described in the patent to Eppler, No. 1,108,560, dated August 25, 1914. The machine comprises an oscillating curved hook 70 needle 2, a needle guide 4, a looper 6, a thread arm 8, a take-up 10, a tension device 12, a channel guide 14, a back gage 16, and a back rest 18.

The needle, needle guide, looper, thread 75 arm, take-up, tension device, back gage and back rest of the present machine have the same construction, arrangement and mode of operation as the corresponding parts of the machine illustrated and described in applicant's application, Serial No. 166,943, of 80 which the present application constitutes a division.

The channel guide of the present machine is made up of two parts arranged side by 85 side. In the drawings the two parts of the channel guide are indicated as 20 and 22. The two parts of the channel guide are formed with work-engaging, blade-like ends 90 for engagement in the channel in the usual manner. The two parts of the channel guide are mounted upon the feed slide to reciprocate therewith and are arranged to oscillate upon the feed slide to carry their work-engaging ends toward and from the 95 bottom of the channel. The part 20 of the channel guide carries a feed point 24 arranged to project into the stock below the between-substance of the sole at the bottom of the channel so as to cause the shoe to be 100 advanced with the channel guide during the forward movement thereof in the direction of feed during each cycle of operation. The oscillating movement of the part 20 of the channel guide is somewhat greater in amplitude 105 than that of the part 22, so that the feed point 24 is withdrawn back of end of the part 22 of the guide before the guide

is retracted in the direction of feed, and the feed point is projected beyond the end of the part 22 before the guide is advanced in the direction of feed. The part 20 of the 5 channel guide is secured by a screw 26 to a lever 28 pivoted by means of a stud 30 upon the feed slide 32. The screw 26 engages in a slot 34 in the part 20 of the guide, the slot permitting a vertical adjustment of the part 20 upon the lever 28. The 10 part 22 of the guide is secured by screws 36 (Figs. 2 and 4) to a plate or block 38 which is secured by a screw 40 to a lever 42 pivoted by means of a stud 44 upon the feed 15 slide 32. The screw 40 engages in a slot 46 in the plate 38 which permits the vertical adjustment of the plate on the lever 42. The plate is adjusted vertically on the lever by means of an adjusting screw 48 threaded 20 into the lever and having a flange or collar 50 engaging in a groove in the plate. The feed slide 32 is mounted to reciprocate longitudinally upon the stud 52 secured at one end in the frame of the machine. The 25 levers 28 and 42 are held from movement longitudinally on their respective pivot studs 30 and 44 so that they reciprocate with the feed slide. Pivotal movement of the feed slide upon the stud 52 is prevented by the 30 engagement of a block 54 formed at one end of a stud 56 secured in the frame of the machine in a slot in an arm 58 on the feed slide. The mechanism for reciprocating the feed slide comprises a lever 60 mounted 35 upon pivot studs 62 and 64, and having an arm 66 formed with a slot 68 (Fig. 3) in which is secured a stud 70 upon the upper end of which is pivoted a block 72 engaging in a groove 74 in the under side of the feed 40 slide. Upon the rear end of the arm 66 is mounted a cam roll 76 engaging in a cam groove in the cam disk 78 mounted on the main shaft 80 of the machine. The lever 42 is oscillated on its pivot stud to carry 45 the acting end of the part 22 of the guide toward and from the bottom of the channel, and connections are provided for oscillating the lever 28 from the lever 42 to project the feed point and withdraw it back 50 of the acting end of the part 22 of the guide as the acting end of the part 22 is moved toward and from the bottom of the channel. The oscillating movements of the lever 42 upon its pivot stud 44 are produced 55 through the movements of an arm 82 secured to one end of a rock-shaft 84 mounted in a bearing on the frame of the machine. A block 86 is pivoted upon a stud 88 secured in the outer end of the arm 82, and 60 engages in a slot 90 in an arm 92 on the lever 42. To enable the effective length of the arm 82 to be adjusted to regulate the amplitude of movement imparted to the lever 42, the arm is secured to a block 94 65 formed on one end of the shaft 84 by means

of a screw 96 passing through a slot 98 in the arm. To the opposite end of the shaft 84 is secured an arm 100 carrying a cam roll 102 engaging a cam groove in the cam disk 78. The lever 42 is formed with an arm 104 substantially parallel with the arm 92, the arm 104 being connected with the arm 92 by a curved web 106. The arm 104 is connected with an upwardly extending arm on the lever 28 by means of a link 108. The 70 lever 28 thus receives oscillating movement from the lever 42. It will be noted from an inspection of the drawings, and more particularly Fig. 4, that the pivot stud 44 of the lever 42 is considerably nearer the 75 work-engaging end of the channel guide than the pivot stud 30 of the lever 28, so that the movement of the acting end of the part 20 of the channel guide is greater than that of the acting end of the part 22. The 80 rear end of the link 108 is connected with the arm 104 by means of a stud 110 mounted in a block 112 secured in a slot 114 in the arm 104. The forward end of the link 108 is connected with the lever 28 by means of 85 a stud 116 secured in a slot 118 in the lever. The stud 110 may be adjusted by the adjustment of the block 112 in the slot 114, and the stud 116 may be adjusted in the slot 118 to vary the extent or the amplitude 90 of the oscillating movement imparted to the lever 28 by the lever 42. With this construction and arrangement of the mechanism for actuating the parts of the guide, as the lever 42 is actuated to withdraw or 95 disengage the part 22 of the guide from the bottom of the channel the lever 28 will be actuated to impart a movement of greater amplitude to the part 20 of the guide to disengage the end of the part 20 of the guide 100 from the bottom of the channel and to withdraw the feed point within the acting end of the part 22. When the lever 42 is 105 actuated to move the acting end of the part 22 of the guide toward the bottom of the channel, the lever 28 will be actuated to impart a movement of greater amplitude to the part 20 on the channel guide to engage the acting end of the part 20 with the bottom of the channel and to project the feed 110 point beyond the part 22. The parts of the guide are constructed and arranged so that at the end of feeding movement of the feed slide the part 20 lies just at one side of the path of the needle so as to support the work 115 firmly against the thrust of the needle as the needle pierces the work. The parts of the guide remain in engagement with the bottom of the channel during the work-piercing stroke of the needle, after which 120 they are actuated to disengage their work-engaging ends from the channel bottom, the movement of the part 20 of the guide withdrawing the feed point back of the acting 125 end of the part 22. During the return move- 130

ment of the guide in the direction of feed, if the end of the part 22 of the guide drags along the bottom of the channel, the feed point is withdrawn far enough so that it 5 does not catch in and cut or tear the stock.

Figs. 5 to 8 inclusive illustrate the manner in which the channel guide operates during each cycle of operation. Fig. 5 shows the position of the parts at a point in a cycle 10 of operations just before the work is fed. It will be noted that the acting ends of both of the parts of the channel guide are engaged with the bottom of the channel, and that the feed point is firmly engaged in the 15 stock. In feeding the shoe the channel guide moves from the position shown in Fig. 5 to that shown in Fig. 6, so that the forward side of the part 20 of the guide lies close to the path of the needle. The width of the 20 channel guide is considerably less than the combined width of, or the distance taken up by, the feed point and awl in the usual machines of this type, so that the shoe may be turned much more readily during the feeding 25 of the shoe. In such machines, the turning of the work upon the feed point as a fulcrum enlarges the opening made by the feed point in the stock, and the turning of the work on the channel guide often causes the feed point 30 to tear or cut the stock, and also often results in disengaging the feed point from the stock before the feeding of the shoe is completed. Because of the proximity of the 35 sides of the channel guide to the feed point, which is located substantially in the center thereof, there is no particular tendency to disengage the feed point from the stock during the turning of the shoe. Furthermore, the work is turned on the acting end of the 40 channel guide and not upon the feed point, so that there is no tendency to enlarge in this way the hole made by the feed point, and thus weaken the stock. Also there is no 45 tendency of the feed point to tear the stock during the turning of the shoe. As shown in Fig. 9, the feed point projects from the channel guide in a direction substantially in line with the end of the channel guide looking from the side thereof, so that it 50 projects into the stock below the line of penetration of the needle indicated by the dotted line in Fig. 9, or below the between-substance, thereby avoiding the weakening of the between-substance by making a puncture 55 therein. Both of the parts of the channel guide remain in engagement with the bottom of the channel during the work-piercing stroke of the needle, thereby firmly supporting the work against the thrust of the 60 needle. Before the channel guide moves back in the direction of the line of feed, the part 65 22 of the guide is actuated to carry its acting end away from the channel bottom, and the part 20 of the guide is actuated to withdraw the feed point back of the acting end

of the part 22 of the guide, as shown in Fig. 7. The end of the part 22 of the guide may drag along the bottom of the channel as the channel guide is retracted in the direction of feed, and the withdrawal of the feed point 70 back of the end of the part 22 of the guide prevents the feed point from catching in the stock and tearing it during the retracting movement of the guide. Fig. 8 shows the position of the parts after the channel guide is 75 retracted. When the channel guide has reached its retracted position in the direction of the line of feed, the part 22 of the guide is actuated to engage its acting end with the bottom of the channel, and the part 80 20 is actuated to project the feed point beyond the end of the part 22 of the guide, and to engage the end of the part 20 of the guide with the bottom of the channel. With this construction, the leaving of a puncture in the 85 between-substance at one side of the needle puncture, and thereby weakening the between-substance, as is often done in the usual machine of this type, when either the needle or the awl is bent out of position, is avoided. 90

Having explained the nature and object of the invention, and having specifically described a machine embodying the invention in its preferred form, what is claimed is:

1. An inseam shoe sewing machine, having 95 in combination, stitch forming devices including a hook needle, a guide for engagement in the channel, a feed point arranged in advance of said guide in the direction of feed to engage the work upon the side of the between-substance opposite the needle, and means for advancing the feed point in the direction of feed into a limiting position out of line with the needle and for retracting the feed point, and for moving the channel 100 guide with the feed point. 105

2. An inseam shoe sewing machine, having 110 in combination, stitch forming devices including a hook needle, a guide for engagement in the channel, a feed point arranged in advance of the guide in the direction of feed to engage the work upon the side of the between-substance opposite the needle, and means for advancing the feed point in the direction of feed into a limiting position out 115 of line with the needle and for retracting the feed point.

3. An inseam shoe sewing machine, having 120 in combination, stitch forming devices including a hook needle, a guide for engagement in the channel arranged to engage the work on the side of the between-substance opposite the needle, a feed point arranged in advance of the channel guide in the direction of feed to engage the work on the 125 guide side of the between-substance, and means for advancing the feed point in the direction of feed to a limiting position out of line with the needle, and for retracting the feed point. 130

4. An inseam shoe sewing machine, having in combination, stitch forming devices including a hook needle, a guide for engagement in the channel arranged on the 5 side of the between-substance opposite the needle, a feed point arranged in advance of the guide to engage the work on the guide side of the between-substance, and means for advancing the feed point in the 10 direction of feed to a limiting position out of line with the needle and for retracting the feed point and for advancing the guide in the direction of feed and for retracting the same with the feed point. 15 5. An inseam shoe sewing machine, having in combination, stitch forming devices including a hook needle, a channel guide, a feed point carried by the channel guide, means for reciprocating the channel guide 20 in the direction of feed, and means for oscillating the guide to project the feed point into and withdraw it from the stock and to carry the acting end of the guide toward and from the bottom of the channel. 25 6. An inseam shoe sewing machine, having in combination, stitch forming devices including a hook needle, a two part channel guide, a feed point carried by one of the parts of the channel guide, means for reciprocating the channel guide in the 30 direction of feed, and means for relatively moving the parts of the guide to project the feed point carried by one of the parts beyond the acting end of the other part and to 35 withdraw the feed point back of the acting end of the latter part. 7. An inseam shoe sewing machine, having in combination, stitch forming devices including a hook needle, a two part channel 40 guide, a feed point carried by one of the parts of the guide, means for reciprocating the latter part of the guide in the direction of feed and means for relatively moving the parts of the guide to project the feed point carried by one of the parts beyond the acting end of the other part and to withdraw the feed point back of the acting end of the latter part. 45 8. An inseam shoe sewing machine, having in combination, stitch forming devices including a hook needle, a two part channel 50 guide, a feed point carried by one of the parts of the guide, means for reciprocating the guide in the direction of feed and means for moving the parts of the guide to carry their acting ends toward and from the bottom of the channel and to project the feed point carried by one of the parts beyond the 55 acting end of the other part and to withdraw the feed point back of the acting end of the latter part. 9. An inseam shoe sewing machine, having in combination, stitch forming devices including a hook needle, a channel guide, a feed point carried by the channel guide and means for actuating the channel guide to feed the work. 10. An inseam shoe sewing machine, having in combination, stitch forming devices including a hook needle, a feed point, and means for advancing the feed point in the direction of feed to a limiting position out of line with the needle and for retracting the feed point and for moving the channel 70 guide in the direction of feed to a limiting 75 position close to the side of the path of the needle and for retracting the same with the feed point. 11. An inseam shoe sewing machine, having in combination, stitch forming devices including a hook needle, a channel guide, a feed point arranged to engage the sole inside the channel at a point intermediate the ends of the line of engagement of the channel guide with the sole, and means for actuating the feed point. 12. An inseam shoe sewing machine, having in combination, stitch forming devices including a hook needle, a guide for engagement in the channel of a shoe, a feed point, and common means for oscillating the guide to carry its acting end toward and from the bottom of the channel and for oscillating the feed point to engage it with and disengage it from the stock. 13. An inseam shoe sewing machine having, in combination, stitch forming devices including a hook needle, channel guide mechanism comprising a guide for engagement in the channel of a sole and means for oscillating the guide to carry its acting end toward and from the bottom of the channel, a feed point, and a connection for actuating the feed point to engage it with and disengage it from the stock from the guide mechanism. 14. An inseam shoe sewing machine, having, in combination, stitch forming devices including a hook needle, a guide for engagement in the channel of a shoe, an oscillating lever upon which the guide is mounted, a feed point, an oscillatory lever upon which the feed point is mounted, means for oscillating one of the levers and a link connecting the levers for causing the oscillation of the other lever from the first lever. 110 115

FRANK CHATEAUNEUF.
